UNITED STATES PATENT OFFICE.

ERLING OYEN, OF DETROIT, MICHIGAN, ASSIGNOR TO DETROIT ELEVATED CORPORATION, OF DETROIT, MICHIGAN, A CORPORATION OF MICHIGAN.

RAILWAY SWITCHOVER.

Application filed January 13, 1922. Serial No. 528,898.

To all whom it may concern:

Be it known that I, ERLING OYEN, a subject of the King of Norway, residing at Detroit, county of Wayne, State of Michigan, have invented a certain new and useful Improvement in Railway Switchovers, and declare the following to be a full, clear, and exact description of the same such as will enable others skilled in the art to which it pertains to make and use the same, reference being had to the accompanying drawings, which form a part of this specification.

My invention relates to a switch-over for a railway system in which, in addition to the traction rails, overhead guiding rails are provided. The object is to provide a switch mechanism capable of simultaneously establishing or disestablishing the switch-over in both traction and overhead rails.

20 A further object is to accomplish the foregoing purposes with a type of construction in which the lateral stresses imposed on the overhead rails by the moving car will be taken up by the trestle work and track structure.

25 A further object is to provide a suitable overhead switch-over adapted for simultaneous operation with the traction rail switch-over which overhead switch-over is of such a character that as the cross-over rail needed to make the switch is brought into position to establish the cross-over the cross-over rail not needed is moved out of the way so it will not interfere with the travel of the railway car and its overhead railway track engaging and collector mechanism.

30 A further object is in the accomplishment of the above purposes, the provision of a switch-over mechanism in which the overhead cross-over rails are moved in a vertical plane and the lower traction rails are moved horizontally to make or break the switch.

35 A further object is to provide a suitably balanced switch mechanism of sturdy construction which is easy of operation and of such a character that the traction rail cross-over and overhead guiding rail cross-over may be simultaneously actuated to establish or disestablish the cross-over.

40 These and other objects together with details of construction will more fully appear from the following description, appended

claims and accompanying drawings, in which:

Figure 1 is a plan view of the traction rails 55 at the cross-over.

Fig. 2 is an elevation partly in section taken on line 2—2 of Fig. 1.

Fig. 3 is an elevation partly in section of a part of the switch actuating mechanism. 60

Fig. 4 is a plan of the guiding rails at the switch-over.

Fig. 5 is a side elevation partly broken away of the switch actuating mechanism for both upper and lower rails. 65

Fig. 6 is an elevation of the main rocker arm.

Fig. 7 is a plan of the construction shown in Fig. 6.

Fig. 8 is a side elevation of one of the supporting standards for the main rocker arm. 70

Fig. 9 is a cross section taken on line 9—9 of Fig. 7.

Fig. 10 is a cross section taken on line 10—10 of Figs. 4 and 11. 75

Fig. 11 is a cross section taken on line 11—11 of Fig. 10.

Fig. 12 is an enlarged plan broken away of the rocker crank shown in Fig. 11.

Fig. 13 is a section taken on line 13—13 80 of Fig. 10.

Fig. 14 is a section taken on line 14—14 of Fig. 10.

My railway system comprises a single traction rail and a pair of overhead guiding rails 85 supported by a suitable trestle work. The switch-over for the traction rails comprises a pair of laterally shiftable traction rail sections adapted to be moved to make or break the gap between the stationary traction rail 90 sections. The switch-over for the overhead guiding rails comprises a pair of vertically movable guiding rail sections carried by a superstructure supported on the trestle work over the guiding rails, said cross-over guiding rail sections disposed for individual vertical movement and adapted to be lowered into position to establish the cross-over simultaneously with the lateral shifting of the corresponding cross-over sections for the 100 traction rails.

In the drawing let 20 (Fig. 1) indicate the single traction rail of the main line, and 21 a diverging traction rail, and 22 the continua-

tion of the main line traction rail 20 connected therewith by a cross-over rail. The switch-over comprises two movable traction rail sections 23 and 24 pivoted at one end as shown in Fig. 1 at 25 in vertical alignment with the stationary rail of the main line and switch-line and movable from such pivot so that the free end may be moved to lie against the main rail 20 to form a continuous traction rail between the main rail section 20 and the diverging section 21 or the continuing main rail section 22.

Switch-over rails 23 and 24 are connected for simultaneous lateral movement by means of a pivoted link 26 so that when section 23 is moved to the position shown in Fig. 1 to establish the switch between lines 20 and 21 the cross-over rail 24 is shifted to disestablish the connection between sections 20 and 22.

The cross-over rails 23 and 24 may be actuated by means of a manually operable switch lever 27 shown in Fig. 5 to which is secured one end of a link 28, the opposite end of which link is connected with a lever 29 which is so mounted on an upright shaft 30 as to reciprocally rotate the shaft about its vertical axis. This shaft 30 is suitably supported at one end having a bearing 30^a at the lower end and 35 near the upper end. Near the lower end is secured a lever 31 to which is pivoted a link 32 which link is connected with one arm of a reducing bell crank 32^a, which crank has a bearing 32^b. The other arm of the crank is linked up with the cross-over rails by means of a turnbuckle 33, and arm 34 which arm is pivoted directly to the rail. This construction is shown in Figs. 1 and 2 and provides a suitable system of linkage whereby the cross-over traction rail sections may be operated by the switch lever 27. Either rail section will, when swung into place, lie with its free end against the main line rail and the other end, being pivoted in the vertical center plane of the main rail, will form a connection for the truck wheels to allow same to travel on said main line rail. The disestablished switch rail section is then away from the main rail so as not to interfere with the flanges of the wheels passing over the rail section which is in place for travel.

When it is desired to switch a car over to a siding or to a rail diverging from the main rail, the first-mentioned rail section is swung out from the position in which it is maintained when the main line is open for travel. The second rail section is simultaneously swung into place so it will rest with its free end against the main rail and the other end being pivoted in the vertical plane of the diverging rail, it will form a connection between the main line and the diverging line, whereby the car will be switched off from the main line and allowed to travel on the line diverging from this main line.

The first-mentioned rail section is then swung out far enough to provide free travel for the wheels without any obstruction of the wheel flanges.

The main rail is cut away for a short distance to permit of this clearance and is so shaped on its free end that it will insure smooth travel of the wheels without any obstacles. One method used for pivoting and operating the rail section is shown in the drawing, but it is understood that the detail construction for the operation of these rail sections will not be confined to this particular construction.

The upper end of shaft 30 is provided with a suitable bearing 35 in the superstructure, shown as broken away in Fig. 5. Mounted on the upper end of this shaft 30 is a bevel gear 37, which is in mesh with a reduced bevel gear 38. Gear 38 is mounted on a shaft 39, which has a bearing at one end in the enclosing gear casing 40, and at the other end is suitably supported by a bracket 41. Mounted on shaft 39 to rotate therewith is an arm 42. The gear ratio is so arranged that when the switch lever 27 is thrown a full distance in either direction gear 38 rotates through an arc of 180 degrees thereby rotating the arm 42 through an equal arc.

Pivoted to the free end of the arm 42 is a link 43 the opposite end of which is connected by means of a suitable pivotal connection 44 with a crank shaft 45 which forms a part of the main rocker frame 46 (Figs. 6 and 7) which frame is itself pivotally supported at opposite sides by means of corresponding projecting shaft ends 47 each having a bearing in suitable supporting standards 48 so that the frame may be rocked within its supports. A turnbuckle connection 50 is shown in Fig. 4 as connecting the link 43 with the link 44. It is apparent that this system of linkage could be widely varied without departing from the invention.

The rocker frame 46 is mounted between the supports 48 for oscillatory rotation through an arc of 180 degrees when the switch lever is thrown in either direction. Frame 46 is provided with four laterally projecting pivots 51, 52, 53 and 54, one at each corner as shown in Fig. 6 and pivotally mounted on each pivot is a corresponding link, such links being indicated as 55, 56, 57 and 58, Figs. 4, 6 and 7.

The opposite ends of these links engage rocker arms which, through suitable connections hereinafter described, serve to raise and lower the cross-over rail sections for the overhead guiding rails. As the connecting links are each engaged with the main rocker frame it will be seen that the cross-over rails will be operated simultaneously.

The overhead track system comprises, as

shown in Fig. 4, a pair of main line rails indicated as 59 and 60, and diverging switch rails indicated as 61 and 62. The continuations of the main line rails beyond the cross-over are indicated as 63 and 64. In construction 59 and 61 form a continuous rail, and 60 and 64, the other outer rail, likewise form a continuous rail. The cross-over rail section for the main line rails 59 and 63 is indicated as 65, and the cross-over for the diverging rail 62 and the main line rail 60 is indicated as 66. The ends of the cross-over rails and stationary rails which they engage are of course so shaped that the movable rail sections come into place against the stationary rail sections in such a manner as to form a continuous rail connection. In Fig. 4 of the drawing, which is a plan of the overhead track structure, I have used for the sake of convenience the above numerals as referring to the rails in their assembly with their supporting channel sections. In Fig. 10 where the rails proper are shown in cross section, they are indicated with suitable subletter "a" combinations, and the channel sections proper by subletter "b" combinations.

In Fig. 10 of the drawing, rails 61^a and 64^a, shown in cross section and supported by channel beams 61^b and 64^b respectively, form a stationary part of the track system and serve as the outer stationary continuous rails, likewise shown in Fig. 4, and indicated in assembly with the channel beam sections as 59 and 61, and 60 and 64 respectively. The movable rails 65^a and 66^a are suitably carried by vertically movable rail tracks so as to establish or disestablish the cross-over. In mounting these rail tracks I have provided for each track a superstructure guiding frame indicated as 67. These guiding frames are supported by the cross members 49 of the trestle work and as there is a supporting truck or carriage provided for each end of the cross-over rail there is a guiding frame positioned above each end of each cross-over rail. These frames have vertically disposed fixed guiding rails 68 which are engaged by double flange truck wheels 69 which wheels are mounted in pairs on opposite sides of a carriage 70. Securely fastened to the under side of the carriage 70 is the channel beam section which carries the guiding rail. As shown in Fig. 11 the carriage 70 is illustrated as supporting the channel beam section 66^b which carries the cross-over rail 66^a. Positioned above each carriage is a suitably mounted rocker crank 71 which, by means of a pivotally depending connecting rod 72, supports the carriage 70. The lower end of this connecting rod 72 is pivoted within a suitable cradle 73 fastened to the carriage, the upper end of the connecting rod is pivoted directly to the crank 71.

This, therefore, provides a construction adapted to vertically reciprocate the carriage 70, as guided by the rail 68, when crank 71 is rocked. This rocking crank has a bearing between suitably supported standards 74 which form a part of the stationary superstructure. One end of the crank is extended beyond its support as shown in Fig. 11 and is provided with a crank lever 75 which has an upwardly projecting pivot 76. The connecting links previously referred to, as being pivoted at one end to the main rocker frame, are individually attached to these several pivots 76 as shown in Fig. 4 so that all the rocker cranks will be operated at the same time to elevate or depress their respective cross-over rails.

The two carriages, which are adapted to elevate the cross-over rail 66, are connected by means of links 57 and 58 with the main rocker frame 46. The two carriages which are adapted to elevate or lower cross-over rail 65, are connected by means of links 55 and 56 with the main rocker frame. The main rocker frame 46 is oscillated through an arc of 180 degrees at each throwing of the switch lever and it is apparent, therefore, that as one cross-over rail is elevated the cross-over rail is lowered to establish the switch and vice versa. The elevation of either cross-over rail is sufficient to permit clearance for the collector mechanism and the guiding truck mechanism mounted on the railway car.

The two rails and their operating carriages are furthermore suitably balanced in order to insure a minimum of required lifting force. It is obvious that though the illustrations show movable cross-over rail sections, as operated by a manually operable system of cranks, that the operation might be otherwise accomplished and this invention is of course not limited to the exact structure shown.

As shown, the entire switch mechanism is so constructed that when the lower traction cross-over rail is operated to make the cross-over the corresponding overhead guide rail section is lowered to establish the switch, and the other guide rail cross-over section is elevated out of the way.

What I claim is:

1. In a railway switch mechanism, in combination, stationary traction rail sections, interposed switch-over rail sections movable horizontally to make or break the gap between the stationary rail sections, stationary overhead guiding rail sections, interposed switch-over rail sections movable vertically to make or break the gap between the stationary guiding rail section.

2. In a switch-over for a railway system comprising stationary traction rails and stationary overhead guiding rails, a movable cross over section for each set of rails, the

overhead cross-over section mounted for movement vertically, the traction rail cross-over section mounted for movement horizontally, means for simultaneously shifting 5 said cross-over sections to make or break the switch in the stationary rail sections in which they are respectively interposed.

3. In a switch-over for a monorail railway system comprising lower stationary traction 10 rail sections and pairs of stationary substantially parallel overhead guiding rail sections, a movable cross-over interposed to make or break the gap between the stationary traction rail sections, a movable 15 cross-over interposed to make or break the gap between the pairs of overhead guiding rail sections, means for simultaneously shifting said cross-overs.

4. In a monorail railway system having a 20 single traction rail, in combination with a switch-over for said traction rail, pairs of over head substantially parallel stationary guiding rails, a vertically movable switch-over interposed therein adapted for movement simultaneously with the traction rail 25 switch-over.

5. In a railway system having stationary overhead guiding rails, a cross-over disposed therein adapted to be lowered to establish the cross-over and elevated to disestablish the cross-over.

6. In a railway system having stationary overhead guiding rails comprising a main line and a diverging line, a pair of vertically movable cross-over rails one for each line so mounted as to be lowered into position to establish the cross-over and elevated to disestablish the cross-over, said pair of cross-over rails so mounted that as one rail

is elevated the other rail is automatically 40 lowered.

7. In a switch-over for a monorail railway system having stationary traction rail sections, overhead stationary guiding rail sections, a pair of cross-over rail sections for 45 said overhead rails, said cross-over sections adapted to be individually lowered to establish a cross-over, a pair of cross-over rail sections for said traction rails mounted for lateral movement to establish a cross-over, means for shifting said traction rail cross-over sections laterally to establish a cross-over simultaneously with the lowering of either overhead cross-over rail to establish a corresponding cross-over. 50

8. In a monorail railway system having a traction rail and overhead guiding rails, in combination, stationary traction rail sections, a movable rail section interposed therebetween to establish and disestablish 60 the cross-over, stationary overhead guiding rail sections, a vertically movable rail section interposed therebetween to establish and disestablish the cross-over.

9. In a monorail railway system having a traction rail and overhead guiding rails, in combination, stationary traction rail sections, a movable rail section interposed therebetween to establish and disestablish the cross-over, stationary overhead guiding rail 70 sections, a vertically movable rail section interposed therebetween to establish and disestablish the cross-over, and means operable to simultaneously establish and disestablish said cross-overs. 75

In testimony whereof, I sign this specification.

ERLING OYEN.
